UNITED STATES PATENT OFFICE.

CLYDE E. W. GARDNER, OF DETROIT, MICHIGAN, ASSIGNOR TO BURROUGHS ADDING MACHINE COMPANY, OF DETROIT, MICHIGAN, A CORPORATION OF MICHIGAN.

CARRIAGE FOR RECORDING-MACHINES.

1,154,304.

Specification of Letters Patent. Patented Sept. 21, 1915.

Original application filed November 13, 1909, Serial No. 527,787. Divided and this application filed May 25, 1915. Serial No. 30,337.

To all whom it may concern:

Be it known that I, CLYDE E. W. GARDNER, a citizen of the United States, residing at Detroit, in the county of Wayne and State 5 of Michigan, have invented certain new and useful Improvements in Carriages for Recording-Machines, of which the following is a specification.

This application is a division of my application filed November 13, 1909, Serial No. 527,787, and relates to tabulating means.

The object is to provide an improved form of means of a simple and practical character whereby infinite variation may be had in the 15 matter of predetermining columnar positions of the carriage.

In the drawings which accompany and form part of this specification, Figure 1 represents a top plan view of the carriage of an adding machine, the same being 20 equipped with my improved tabulating mechanism; Fig. 2 is a right side elevation of the same; and Fig. 3 is a vertical cross-section taken substantially on line 3—3 of 25 Fig. 1.

The reference letter A designates a roller platen and B the side plates of the carriage, in bearings upon which the said roller platen is journaled. The reference letter C designates 30 a fixed bracket or rail in which the carriage is mounted to travel transversely of the machine. It will be understood that the side plates are connected by suitable tie-bars and cross rods and that suitable devices are 35 employed for guiding the paper and feeding it around the platen. As these constitute no part of my present invention I deem it unnecessary to include a detailed description of them.

The tabulating devices which embody my present invention comprise a pair of arms 31 located at opposite ends of the carriage bracket C and pivoted respectively (by pivot screws 33) to ears formed upon a 1 projecting rearwardly from the said stationary bracket. A screw-threaded rod or shaft 30 extends between the upper ends of said arms 31, being suitably engaged with bosses on said arms as illustrated in Fig. 1. Nuts H 45 are engaged with this screw-threaded rod and adjustable along it by rotation thereon. These nuts are circumferentially grooved at the middle and tapered or made frustoconical on each side of the groove, as also

shown in Fig. 1. These nuts are further 55 formed with flat faces at opposite sides, as illustrated in Figs. 2 and 3, for the purpose of locking them in adjusted positions along the screw-threaded rod 30. The stationary bracket C has a rearwardly extending portion which presents a vertical face 34 to the nuts and coöperates with the flat faces thereof to lock them from turning. Springs 35 connect the arms 31 to the bracket C, as shown in Fig. 3, in such manner as to draw 60 forward the tabulating structure comprising the two arms, the screw-threaded rod and the nuts, and thereby yieldingly maintain the locking relation between the nuts and the vertical face 34 of the stationary bracket, 70 as clearly illustrated in Fig. 3.

A rock shaft 36 extends from side to side of the carriage and is suitably journaled in the side plates B thereof and also in central bearing lugs which project rearward from the base portion of the carriage. Between these lugs there is mounted upon and secured to the said rock shaft 36 an arm or finger 32 which is designed to engage the circumferential grooves of the nuts H. At the 80 right hand end the rock shaft 36 projects beyond the side plate of the carriage and there is secured to it a lever 37 which serves as a handle being formed at its upper end with a finger piece. The forwardly projecting arm of this lever is connected by a spring 38 to an upper portion of the adjacent side plate of the carriage. It will be seen that this spring exerts itself to force the arm or finger 32 downwardly into engagement with the nuts H. Obviously the 85 said arm or finger 32, so mounted upon the carriage, is adapted to fix its lateral position by engagement with one or the other of the said nuts. By pulling forward the 90 handle 37 this arm or finger may be disengaged from one of said nuts and the carriage then shifted to a position where this arm or finger will engage another of said nuts. This latter engagement may take 95 place in an automatic manner since, as before pointed out, the nuts are beveled. That is to say, if, after the tabulating finger has been disengaged from one nut and finger pressure is not then maintained upon the 100 lever 37 while the carriage shifts to its new position, the said finger will ride into the 105 groove of the next nut through coaction

with the bevel thereof, and if the carriage is being impelled by motive power there will be a retardation as it approaches the new position, due to the frictional engagement 5 between the finger and the bevel of the nut.

The pivotal mounting of the tabulating structure which comprises the arm 31, the screw-threaded rod 30 and the nuts, provides for swinging the same rearwardly 10 away from the vertical nut-locking face 34 of the stationary bracket C far enough to permit rotation of the nuts for adjusting them along the rod 30.

It will now be seen that the above described construction is well adapted to accomplish the objects primarily stated, though of course it is susceptible of modification to a greater or less extent without necessarily departing from the spirit and 20 scope of the invention.

I claim:

1. The combination with a frame, of a carriage and platen movable thereon, a threaded shaft parallel to said frame and 25 movable with relation thereto, flat sided nuts adjustable on said shaft and adapted to serve as stops, and means tending normally to hold said shaft against said frame whereby the nuts will be prevented from 30 turning.

2. The combination with a frame, of a carriage and platen movable thereon, a threaded shaft parallel to said frame, arms carrying said shaft so pivoted as to bring 35 said shaft against said frame, springs tending to draw said shaft toward the frame, and a plurality of nuts on said shaft having their opposite sides flattened whereby when in contact with the frame they cannot 40 be accidentally turned and displaced.

3. In a recording machine, the combination with a laterally movable paper carriage, of tabulator stop elements, the one comprising a screw-threaded rod or shaft 45 and nuts thereon, and the other an abutment member to engage the nuts; one such element being mounted on the carriage and the other on the fixed frame or support; together with means for locking the nuts 50 through their engagement with a part on the shaft-supporting structure between which part and the nuts there is relative movement transverse the shaft for unlocking purposes.

4. In a recording machine, the combina-

tion with a laterally movable paper carriage, of tabulator stop elements, the one comprising a screw-threaded rod or shaft and flat-sided nuts thereon and the other an abutment member to engage the nuts; one 60 such element being mounted on the carriage and the other on the fixed frame or support; together with means for locking the nuts through engagement of their flat sides with a part on the shaft-supporting structure between which part and the nuts there is relative movement transverse the shaft for unlocking purposes.

5. In a recording machine, the combination with a laterally movable paper carriage, of tabulator stop elements, the one comprising a screw-threaded rod or shaft and bevel-ended nuts thereon, and the other a spring-held abutment member to engage the nuts; one such element being mounted 70 on the carriage and the other on the fixed frame or support; together with means for locking the nuts through their engagement with a part on the shaft-supporting structure between which part and the nuts there is relative movement transverse the shaft for 75 unlocking purposes.

6. In a recording machine, the combination with a laterally movable paper carriage, of tabulator stop elements, the one comprising a screw-threaded rod or shaft and flat-sided and bevel-ended nuts thereon, and the other a spring-held abutment member to engage the nuts; one such element being mounted on the carriage and the other on the fixed frame or support; together with means for locking the nuts through engagement of their flat sides with a part on the shelf-supporting structure between which part and the nuts there is relative movement transverse the shaft for 80 unlocking purposes.

7. A tabulating mechanism for recording machines comprising, in combination with the frame and carriage, a screw threaded 90 shaft, nuts thereon having annular grooves and beveled end portions, and a stop member to engage the grooves and co-operate with the beveled end-portions of the nuts, substantially as and for the purpose described.

CLYDE E. W. GARDNER.
